UNITED STATES PATENT OFFICE.

DENIS MACHELL HOLLINS, OF BLACKBURN, ENGLAND, ASSIGNOR TO DRAPER CORPORATION, OF HOPEDALE, MASSACHUSETTS, A CORPORATION OF MAINE.

WEFT-CUTTING MEANS FOR AUTOMATIC WEFT-REPLENISHING LOOMS.

Application filed June 14, 1924. Serial No. 720,021.

To all whom it may concern:

Be it known that I, DENIS MACHELL HOLLINS, a subject of King George V of Great Britain, residing at Blackburn, in the county of Lancaster, England, have invented a new and useful Improvement in Weft-Cutting Means for Automatic Weft-Replenishing Looms, of which the following is a specification.

10 In an automatic weft-replenishing loom it is necessary, when a new bobbin is transferred to the active shuttle, to cut the weft end extending from the selvage to the exhausted bobbin, and also to cut the new weft 15 end extending from the usual weft end holder on the magazine to the selvage.

It is usual to provide, in an automatic weft-replenishing loom, a shuttle feeler to ascertain that the shuttle has properly entered the box prior to a transfer taking place, and such shuttle feeler has commonly associated with it means to cut at the time of transfer the weft of the exhausted bobbin adjacent the mouth of the shuttle box, and 25 to clamp the severed end. It is also usual to provide, adjacent the selvage, means to cut the weft close to the selvage and for the reason that such means are usually associated with or adjacent the temple, they are 30 commonly referred to as the temple thread cutter. This temple thread cutter is usually arranged to cut the outgoing weft end adjacent the selvage, and also the new or incoming weft end at the same point. It is 35 desirable that the cutting of the weft ends at the selvage be performed promptly after a transfer has taken place and this is especially the case if a weft fork be disposed between the temple thread cutter and the 40 shuttle feeler and thread cutter as otherwise the presence of the outgoing and incoming weft ends render the weft fork inoperative, that is to say the weft of the active shuttle may be broken but the weft fork 45 can not function to stop the loom because it is rocked by the outgoing or incoming weft end, or both.

The object of the present invention is to provide an improved construction of temple 50 thread cutter which will normally be inoperative but which on a transfer taking place is rendered operative and functions to sever simultaneously both the outgoing and

incoming weft ends one pick after transfer has taken place, after which it is again put 55 out of operation until the next transfer.

The idea of providing a temple thread cutter which is made operative only at the time of transfer and for a determined period subsequent thereto is not in itself novel but 60 the temple thread cutter and the means for putting it into and out of action, which constitute the present invention are of simpler construction than the devices formerly employed and, by reason of the simultaneous cutting of both the outgoing and incoming weft ends on the pick following a transfer, the weft fork becomes immediately operative to detect possible breakage of the new weft thus assisting materially in the 70 production of perfect fabric.

According to the invention the temple head has associated with it a fixed cutting blade with which is adapted to co-operate a movable cutting blade carried by or 75 formed on the rear end of a bar slidably supported for frontward and rearward movement in suitable guides attached to the temple stand, and acted upon by a spring tending to force it rearwardly. The lower edge of the bar has a notch adapted to co-operate with a fixed catch to hold the bar normally in frontward or inoperative position. The forward end of the bar carries 80 a pivoted latch which is held normally by 85 spring action against a fixed stop and the front face of the latch is bevelled at a suitable angle.

The usual rock shaft by which indication of weft exhaustion is conveyed to the transfer mechanism has mounted upon it an arm or lever, which is adapted to co-operate with the pivoted latch referred to, in a manner which will be described later.

A bowl or stud on the sliding bar is embraced by the forked upper end of a lever mounted on a fixed pivot, the lower end of such lever being cranked and carrying an adjustable abutment screw. Another lever, also mounted on a fixed pivot, is adapted to 95 be rocked by a cam on a constantly revolving shaft. During normal running of the loom the lever last referred to swings idly, but when, as will be hereinafter described, the bar carrying or constituting the movable cutter blade, is projected rearwardly into 100 105

operative position, the lever connected with said bar is moved pivotally into a position in which it is engaged by the cam-operated lever and the latter acts to move the cutter bar forwardly, thus severing the weft and at the same time reinstating the said cutter bar into normal inoperative position.

In the accompanying drawing,

Fig. 1 is a side elevation of an embodiment of the improved weft cutting mechanism, shewing the parts in normal position, and

Fig. 2 is a similar view shewing the sliding cutter bar projected rearwardly ready to perform its cutting operation on the next appropriate movement of the cam-operated lever.

Fig. 3 is a plan view of the mechanism, on a reduced scale.

Referring to the drawing, *a* represents the usual temple, and *b* the temple head. Associated with the latter is a fixed cutting blade *c* which, when the lay *d* is in forward position approaches closely the reed *e*.

Slidably supported, for the forward and rearward movement in guides *f*, *f*, attached to the temple stand *g*, is a bar *h* having its rear end formed as, or having attached thereto, a cutting blade *h'*. A spring *i*, secured at one end to a fixed stud *j* and at the other end to a pin *k* projecting from the bar *h*, tends to project the bar rearwardly, as shewn in Fig. 2, in which position the fixed cutting blade is adjacent the front side of the reed whilst the movable cutting blade extends between and behind the dents of the reed. The lower side of the bar *h* has a notch *h²* adapted to co-operate with a fixed catch *f'* to hold the bar normally in frontward or inoperative position, as shewn in Fig. 1, and a spring *m* is provided to press upon the bar and hold the notch in engagement with the catch.

At the front end of the bar *h* there is pivoted loosely, on a stud *n*, a latch on switch-cam *o* the rear face *o'* of which is held normally against the pin *k*, by means of a spring *p* connecting the said pin with a pin *q* on the switch-cam. The front face *o²* of the switch-cam *o* is suitably bevelled as shewn for the purpose shortly to be described.

The usual rock shaft *r* by which indication of weft exhaustion is conveyed to the transfer mechanism has mounted upon it an arm or lever *s* adapted to co-operate with the switch cam *o*. Normally the arm lies rearwardly of the switch-cam as shewn in Fig. 1. When the rock shaft is operated to initiate a transfer, the arm *s* moves to the position indicated in dotted lines in Fig. 1. In so doing, it contacts with the switch-cam and, moving same pivotally against the spring action, passes to the front side of same, the switch-cam being

returned by its spring into contact with the stop pin *k*.

As the rock shaft *r* returns to normal position, after the transfer has been effected, the upper end of the arm *s* comes into contact with the bevelled front face *o²* of the switch-cam and by its continued rearward movement presses the switch-cam and, consequently the bar *h* upwardly, with the result that the notch *h²* is removed from the catch *f'*. The spring *i* thereupon projects the bar *h* rearwardly into the operative position shewn at Fig. 2, so that as the lay comes forward the movable cutting blade will extend between the dents of the reed.

The outgoing weft end extending from the selvage to the exhausted bobbin, and the incoming weft end extending from the selvage to the weft end holder on the magazine, will thus lie between the fixed and movable cutting blades and frontward movement of the bar *h* at the appropriate time will cause such weft ends to be severed adjacent the selvage.

To effect this forward movement of the bar *h*, a stud or bowl *t* projecting laterally from the bar is embraced by the upper forked end *u'* of a lever *u* mounted on a fixed pivot *v*. The lower end of this lever *u* is cranked as at *u²* and carries an adjustable abutment screw *u³*. A lever *w*, conveniently also mounted on the pivot *v*, is adapted to be rocked by a cam *x* on an appropriately and constantly revolving shaft *y*, which may be the tappet shaft of the loom.

When the cutter bar *h* is in its normal frontward or inoperative position, the lever *w* is actuated without moving the lever *u*, as will be understood from Fig. 1, but when the cutter bar is projected rearwardly as shewn in Fig. 2, the consequent rocking of the lever *u* on its pivot carries the abutment screw into a position in which it will be engaged by the lever *w* as the latter is swung upwardly. On the next succeeding revolution of the cam *x*, therefore, the lever *u* is rocked and carries the cutter bar *h* frontwardly and causes the weft ends at this time extending from the selvage to be severed. The cam *x* is so shaped as to carry the notch *h²* slightly beyond the catch *f'* so that the spring *m* pressing upon the bar *h* causes the notch to engage with the catch, and the bar to be thus retained in frontward inoperative position.

The temple thread cutter, having performed its desired function, of cutting both the outgoing and incoming weft ends on the pick next following the transfer of a new bobbin, remains out of action until released by the next actuation of rocking transfer shaft *r*, the cam-operated lever *w* meanwhile making its swinging movements idly without coming into contact with the abutment screw *u³* of lever *u*.

Having thus described my invention, what I claim as new and desire to secure by Letters Patent is:—

1. In an automatic filling replenishing loom, a temple thread cutter having relatively movable thread cutting means, means tending to place said thread cutting means in operative position, means for holding the thread cutting means in inoperative position during the normal operation of the loom, means, operable by the mechanism for changing the operation of the loom during its restoration to normal position after call for transfer, to release said thread cutting means from inoperative position and means for actuating the thread cutting means when released to cause the same to sever the filling ends extending from the selvage upon the first pick after transfer and thereupon to restore said thread cutting means to inoperative position.
2. In an automatic filling replenishing loom, a temple thread cutter having relatively movable thread cutting means, means tending to place said thread cutting means in operative position, means for holding the thread cutting means in inoperative position during the normal operation of the loom, means, operable by the mechanism for changing the operation of the loom during its restoration to normal position after call for transfer, to release said thread cutting means from inoperative position and continuously operated means acting in synchronism with the movement of the lay to cause said thread cutting means, when released, to sever the filling ends extending from the selvage upon the first pick after transfer and thereupon to restore said thread cutting means to inoperative position.
3. In an automatic filling replenishing loom, a temple thread cutter having a fixed blade and a co-operating spring actuated movable blade, means acting normally to hold said movable blade in inoperative position against the force of its spring, means operable by the movement of the controller rod during its movement to normal position after transfer to release said movable blade and means for actuating said movable blade to cause the same to engage and, in co-operation with the stationary blade, to sever the filling ends extending from the selvage upon the first pick and thereupon to restore the movable cutting blade to inoperative position.
4. In an automatic filling replenishing loom, a temple thread cutter having a fixed blade and a co-operating spring actuated movable blade having a notch positioned to engage a member rigid with the temple stand and to retain said movable blade in inoperative position against the action of its spring, a switch cam on said movable blade, an arm on the controller rod of the
5. In an automatic filling replenishing loom, a temple thread cutter having a fixed blade and a co-operating spring actuated movable blade having a notch positioned to engage a member rigid with the temple stand and to retain said movable blade in inoperative position against the action of its spring, a switch cam on said movable blade, an arm on the controller rod of the loom positioned to engage and pass freely beneath the switch cam when moved in one direction upon call for transfer and to engage said switch cam and release said movable blade during its movement in the opposite direction after call for transfer and means for actuating the released movable blade to cause it to sever the filling ends upon the first pick after transfer and thereupon to restore said movable blade to inoperative position.
6. In an automatic filling replenishing loom, a temple thread cutter having a fixed blade and a co-operating spring actuated movable blade having a notch positioned to engage a member rigid with the temple stand and to retain said movable blade in inoperative position against the action of its spring, a switch cam on said movable blade, an arm on the controller rod of the loom positioned to engage and pass freely beneath the switch cam when moved in one direction upon call for transfer and to engage said switch cam and release said movable blade during its movement in the opposite direction after call for transfer and means including a continuously rotating cam for actuating the released movable blade to cause it to sever the filling ends upon the first pick after transfer and also to restore the movable blade to inoperative position.
7. In an automatic filling replenishing loom, a temple thread cutter having a fixed blade and a co-operating spring actuated movable blade having a notch positioned to engage a member rigid with the temple stand and to retain said movable blade in inoperative position against the action of its spring, a switch cam on said movable blade, an arm on the controller rod of the loom positioned to engage and pass freely beneath the switch cam when moved in one direction upon call for transfer and to engage said switch cam and release said movable blade during its movement in the opposite direction after call for transfer, a bell crank lever having one arm pivotally engaging said movable blade, an oscillating lever positioned to engage the other arm of said bell crank lever upon release of said spring actuated movable blade and operable when so engaged to actuate said movable blade and also to restore the same to inoperative position.
8. In an automatic filling replenishing loom, a temple thread cutter, means, operable by the mechanism for changing the operation of the loom during its restoration to normal position after call for transfer, to place the thread cutter in operative position and means operable to cause the positioned thread cutter to sever the filling ends extending from the selvage upon the first pick after transfer and thereupon to

render the thread cutter inoperative until after the next call for transfer.

8. In an automatic filling replenishing loom, a temple thread cutter having relatively movable thread cutting means, means for holding the thread cutting means in inoperative relation during the normal operation of the loom, a cam rotating in synchronism with the movement of the lay, means for actuating said thread cutter from said cam normally maintained out of operative relation to said cam and means operable by the mechanism for changing the operation of the loom during its restoration to normal position after call for transfer to render said thread cutter operative and to position its actuating means in operative relation to said cam, whereby the actuation of said thread cutter by said cam will cause 20 the same to sever the filling ends extending from the selvage upon the first pick after

transfer and will thereupon restore the thread cutter to inoperative position.

9. In an automatic filling replenishing loom, a temple thread cutter having a fixed 25 blade and a relatively movable blade, means for holding the fixed blade in inoperative position during the normal operation of the loom, means for actuating said movable blade including a cam and a lever connected to said blade and held out of operative relation to said cam when said movable blade is held in inoperative position and means 30 operable by the mechanism for changing the operation of the loom during its restoration to normal position after call for transfer to release said movable blade and to place its actuating lever in operative relation to said cam.

In testimony whereof I affix my signature.

D. M. HOLLINS.
